UNITED STATES PATENT OFFICE

152,691

DESIGN FOR A SOLDERER HOUSING

Willard J. Humpal and Benhard G. Reimers,
Boulder, Colo.

Application May 9, 1947, Serial No. 138,934

Term of patent 14 years

(Cl. D26—5)

To all whom it may concern:

Be it known that we, Willard J. Humpal and Benhard G. Reimers, citizens of the United States, residing at Boulder, Boulder County, Colorado, have invented a new, original, and ornamental Design for Solderer Housing, of which the following is a specification, reference being had to the accompanying drawing, forming part thereof. In the drawing:

Fig. 1 is a three dimensional view of a solderer housing, embodying our new design;

Fig. 2 is a front elevation of the said solderer housing; and

Fig. 3 is a side elevation of the said solderer housing.

We claim:

The ornamental design for a solderer housing, as shown.

WILLARD J. HUMPAL.
BENHARD G. REIMERS.
